DESIGN FOR A CLIP FOR HEARING AIDS

Harold W. Darr, Minneapolis, Minn., assignor to
The Maico Company, Incorporated, Minneapolis, Minn., a corporation of Minnesota

Application September 16, 1944, Serial No. 115,318

Term of patent 14 years

(Cl. D17—3)

To all whom it may concern:

Be it known that I, Harold W. Darr, a citizen of the United States, residing at Minneapolis, in the county of Hennepin and State of Minnesota, have invented a new, original, and ornamental Design for a Clip for Hearing Aids, of which the following is a specification, reference being had to the accompanying drawing, forming part thereof.

Referring to the drawing:

Fig. 1 is a front elevational view of a clip for hearing aids showing my new design;

Fig. 2 is a top plan view; and

Fig. 3 is a side elevational view thereof.

I claim:

The ornamental design for a clip for hearing aids, substantially as shown.

HAROLD W. DARR.
